UNITED STATES PATENT OFFICE.

REUBEN F. KROHN, OF SUNBURY, PENNSYLVANIA.

CAR-COUPING.

SPECIFICATION forming part of Letters Patent No. 225,840, dated March 23, 1880.

Application filed January 6, 1880.

To all whom it may concern:

Be it known that I, REUBEN F. KROHN, of Sunbury, in the county of Northumberland and State of Pennsylvania, have invented a new and Improved Car-Coupling, of which the following is a specification.

Figure 1 is a plan of the device. Fig. 2 is a longitudinal sectional elevation on line *x x*, Fig. 1.

Similar letters of reference indicate corresponding parts.

The object of this invention is to provide a simple and effective self-coupler whereby cars can be coupled or uncoupled and the link removed without going between the cars.

In the drawings, A represents a draw-head provided with a central longitudinal opening, *a*, in its top, within which is pivoted, on the pin *b*, the curved latch or tongue *B*, whose upper surface is flush with the top of the draw-head and whose under surface curves downward, as shown, and rests on the lug *C* below it. *C* is a triangular lug, rigidly fixed with its point forward just within the mouth of the draw-head A, as shown, with the short face of the said lug undercut, as shown at *c*, looking rearward. On a parallel line with this lug *C*, and rearward of it, in the draw-head A, is rigidly fixed the triangular lug *D* on the bottom of the said draw-head. This lug *D* is somewhat lower than the lug *C*, has its short face undercut, as shown at *d*, and is set a short distance from the lug *C* and facing it, so that between the two lugs there is an opening or socket, *f*, shaped somewhat like an egg, with a narrow opening, *g*, in its top for the admission of the coupling-link E.

On either side of the opening *a*, near the mouth of the draw-head A, and passing down through the top plate to the lower plate thereof, are the pins *F*, that serve as guides for an entering link, and may (either of them) be also used to hold the link in the event of the breaking of the lug *C*.

The end of the link E, entering the draw-head between the pins *F*, will, in coupling, move up the inclined face of the lug *C* to its highest point, pushing up the tongue or latch *B* in the latter part of its progress, and as soon as the end of the said link has passed the tip of the said lug *C* the weight of the tongue or latch *B* forces it (the link) down through the opening *g* into the socket *f* between the lugs *C D*, whence it is prevented from drawing out by the lug *C* and prevented from moving rearward by the lug *D*.

A car can be uncoupled and the link E removed through the opening *a* on turning the tongue or latch *B* back, as shown on the right in Fig. 2, avoiding the trouble and danger of going between the cars for such purpose.

Having thus described my invention, I claim as new and desire to secure by Letters Patent—

A car-coupler having the oppositely - concaved lugs *C c D d*, forming the socket *f g*, the guides *F F*, and the rear hinged tongue, *B*, supported on the more elevated front lug, *C*, as shown and described.

REUBEN F. KROHN.
